H. A. SMITH

OPERATING ATTACHMENT FOR WASHTUBS

Filed August 9, 1924

Patented Jan. 5, 1926.

1,568,633

UNITED STATES PATENT OFFICE.

HARRY A. SMITH, OF MONDOVI, WASHINGTON.

OPERATING ATTACHMENT FOR WASHTUBS.

Application filed August 9, 1924. Serial No. 731,122.

To all whom it may concern:

Be it known that I, HARRY A. SMITH, a citizen of the United States, residing at Mondovi, in the county of Lincoln and State of Washington, have invented certain new and useful Improvements in Operating Attachments for Washtubs, of which the following is a specification.

The present invention relates to an operating attachment for washing machines and its object is to provide mechanical means with which the washing may be done in an ordinary tub with ease. The device, which is preferably hand-operated, carries a plunger on the reciprocating and oscillating shaft, and on this plunger the material to be washed is secured by a plurality of clips provided around its edge. In this manner the material is firmly held while being agitated in the water and a thorough cleaning is performed.

In the accompanying drawing, one embodiment of the invention is illustrated, and

Figure 1 is a fragmentary top plan view 25 of the device with some parts broken away;

Fig. 2 is a section on the line 2-2 of Figure 1, and

Fig. 3 is a fragmentary side elevation of 30 a portion of the plunger and the securing means.

In the drawing, the reference numeral 10 represents a wash tub of any well-known type. Upon the top edge of the tub is mounted an annulus 11 which has a downwardly directed flange 12 fitting within the top edge of the tub and around this flange is provided an annular bead or rim 40 which rests on the edge of the tub. The annulus extends some distance above the top edge of 40 the tub and terminates with an inwardly directed annular flange 13. In this manner a considerable depth is added to the tub so that it may hold a greater amount of clothes to be washed than usual. The annulus 11 has three or more depending lips 14 which are threaded and adapted to each receive a thumb screw 15 for clamping the adaptor to the tub.

A lid 16 of slightly greater diameter than 50 the opening 17 formed by the flange 13 on the annulus 11 closes the top of the tub and rests with its outer edge upon the flange 13. At one side of the lid hinges 18 are provided so that the lid may be raised without 55 removing the same from the tub. In order

to secure the lid in locked position, one or more buttons 19 are provided on the flange 13 which are pivoted on rivets 20 in order to be turned inwardly in engagement with the edge of the lid 16.

A carrier 21, preferably made of casting, is bolted, as at 22, on the top of the lid 16. This carrier has a pair of bearings 23 for a horizontal shaft 24 which extends beyond the outer edge of the annulus 11 and is shown as equipped with a crank handle 25, although it is obvious that other means may be employed for rotating the shaft. The inner end of the shaft 24 carries another crank 26 having a spherical head 27 engaging corresponding jaws 28 of a reciprocating bar 29. This bar is adapted to slide in a sleeve 30 secured on the operating shaft 31 of the device.

The operating shaft 31 is carried with its axis vertically in a standard 32 on the carrier 21, as best seen in Figure 2, and is of sufficient length to permit of reciprocation in the standard for the full swing of the crank 26. At the lower end of the operating shaft 31 is secured, by means of a latch 33, a plunger 34. The latter has the shape of a hollow cone and along the outer periphery at the base of the cone are provided clips 35. These clips are preferably made of spring wire and secured on the upper side of the cone in any suitable manner, as indicated in Figure 3. The upper ends of the clips are inclined inwardly from the edge of the plunger. The clips are arcuate and their shanks 36 are spaced apart from each other a short distance to permit the insertion of the material to be washed between the shanks so that the material is firmly held during the operation of the machine.

After the tub has been filled to a sufficient height with hot water and soap suds while the lid is open, the clothes or other material to be washed are secured around the edge of the plunger 34 in the clips 35. The lid is then closed and locked by the latches 19, whereupon the crank handle 25 is turned. The rotary motion of the crank 26 is then converted into an oscillatory and reciprocatory motion of the operating shaft 31 and the plunger 34. The elements for producing this combined motion of the plunger have been more fully shown and described in my Patent No. 1,501,471, and form no part of the present invention.

Having thus described the invention, I claim:

An operating attachment for wash tubs comprising an annulus fitting the top edge 5 of the tub, a plunger suspended in the tub from the annulus, upstanding resilient clothes-retaining clips around the outer periphery of the plunger each consisting of straight side portions secured at their lower

ends to the plunger and arcuate portions 10 connecting the upper ends of the side portions, the clothes being clamped by and between the opposed straight side portions of adjacent clips, and means on the annulus to operate the plunger.

In testimony whereof I affix my signature.

HARRY A. SMITH. [L. S.]
